UNITED STATES PATENT OFFICE.

JOHN W. STEPHENSON, OF TOLEDO, OHIO, ASSIGNOR TO THE NATIONAL MALLEABLE CASTINGS COMPANY, OF CLEVELAND, OHIO, A CORPORATION OF OHIO.

JOURNAL-BOX.

SPECIFICATION forming part of Letters Patent No. 792,943, dated June 20, 1905.

Application filed January 26, 1905. Serial No. 242,746.

To all whom it may concern:

Be it known that I, JOHN W. STEPHENSON, of Toledo, Lucas county, Ohio, have invented a new and useful Improvement in Journal-
5 Boxes, of which the following is a full, clear, and exact description, reference being had to the accompanying drawings, forming part of this specification, in which—

Figure 1 is an elevation, partly in section, 10 of the journal-box and equalizing-bar embodying my invention. Fig. 2 is a vertical section on the line II II of Fig. 1. Fig. 3 is a view similar to Fig. 1, illustrating a modified connection between the equalizing-bar 15 and the journal-box; and Fig. 4 is a vertical section on the line IV IV of Fig. 3.

In the construction of cars in which an equalizing-bar is employed to connect the adjacent journal-boxes on the same side of the 20 car difficulty has been experienced from the fact that the equalizing-bar is apt to sag and cause the boxes to tip laterally upon their pedestals, thus causing strain and wear upon the sides of the box and also upon the brass 25 within the box, thus deteriorating these parts rapidly and constituting a source of annoyance and expense in the maintenance of the cars, besides increasing the friction on the journals of the axles and causing them to heat 30 when in use. I have discovered a simple means by which these difficulties can be overcome by interposing between the equalizing-bar and the axle-box a rocking bearing, so that in case the equalizing-bar sags it will adjust 35 itself automatically to the box and will enable the box at all times to be in upright position parallel with the pedestals without grinding and wearing upon the latter, as above stated.

My invention, broadly considered, may be 40 applied in many forms; but I have shown the preferable construction in the drawings, which I will now describe.

In Figs. 1 and 2, 2 represents the equalizing-bar; 3, the axle-box; 4, the axle; 5, the 45 brass, and 6 the wedge. 77 are the pedestals between which the axle-box is set. I form on the top of the axle-box a rounded seat 8, pref-

erably concave upwardly, on which is set a bearing-piece 9, the bottom of which is a counterpart of the bearing 8 and the top of which 50 is provided with suitable projections 10, engaging a recess 11 on the equalizing-bar, so as to connect the latter to the bearing-piece 9. The use of the parts 10 and 11 is not, however, essential to my invention, since these 55 parts may be otherwise connected.

The bearings 8 and 9, as shown in Figs. 1 and 2, may be spherical in their surface contour, so that the bearings will adjust themselves in any direction, and in case the equalizing-bar should sag or become displaced laterally for any cause this self-adjustment of the bearings will prevent such shifting of the bar from canting the axle-box.

In the modification shown in Figs. 3 and 4 65 the curved bearing between the parts 8 and 9 is cylindrical in contour, so as to afford an adjustment only in the planes parallel to the equalizing-bar, and this construction for most purposes is preferable. In both cases it will 70 be noticed there is a clearance between the parts 10 and 11, so as to allow a slight lateral sliding of the bearing-piece 9 on the equalizing-bar, since this is necessary in order to obtain complete adjustment; but this sliding 75 bearing may be provided for in other ways than as shown.

The parts may be modified. Thus the bearing-surface 8 may be convex and the adjacent surface of the part 9 may be concave. 80

I claim—

1. In combination with a journal-box and equalizing-bar, a rigid bearing-piece affording a rocking bearing between said journal-box and bar; substantially as described. 85

2. In combination with a journal-box and equalizing-bar, a rigid bearing-piece between these parts affording a rocking bearing and affording also a sliding bearing with the equalizing-bar; substantially as described. 90

3. In combination with a journal-box and equalizing-bar, a bearing-piece having a rocking bearing of cylindrical outline on the top of the journal-box, and having a sliding bear-

ing on the equalizing-bar; substantially as described.

4. In combination with a journal-box and equalizing-bar, a bearing-piece having a rock-
5 ing bearing with the top of the journal-box, and having also a sliding bearing on the equal-
izing-bar; substantially as described.

In testimony whereof I have hereunto set my hand.

JOHN W. STEPHENSON.
